UNITED STATES PATENT OFFICE

2,456,239

SECTIONAL TYPE BOILER

William S. Anderson, Jr., Williamsport, Pa., assignor to Aveo Manufacturing Corporation, a corporation of Delaware

Application April 2, 1945, Serial No. 586,086

10 Claims. (Cl. 122—225)

1

The invention relates to boilers.

One object of the invention is to provide a boiler of the sectional magazine feed type which includes water conduits at the sides of the inclined grate with the conduit at the upper end of the inclined grate disposed relatively higher than the water conduit at the other side so as to increase the capacity of the firebox, reduce the height of the water legs and the weight of the sections, and any tendency of the walls of the leg to rust due to moisture in the fuel.

A further object of the invention is to provide a boiler of this type in which the combustion gases are directed longitudinally by baffles on the intermediate boiler sections to travel longitudinally and thence to a flue from which the products of combustion flow to the stack.

A further object of the invention is to provide a boiler of this type with a vent from the fuel magazine to the combustion gases flowing to the stack for preventing any accumulation of combustible gases in the fuel in the magazine and allowing any steam or moisture, usually present in coal, to escape with the combustion gases.

Another object of the invention is to provide ribs on the boiler sections for allowing soot to escape from the longitudinal flue for the combustion gases into the firebox during the cleaning of the boiler.

Another object of the invention is to improve the construction and operation of the sectional magazine feed type of boilers set forth in U. S. Patent No. 1,800,915.

Other objects of the invention will appear from the detailed description.

The invention consists in the several features hereinafter set forth and more particularly defined by claims at the conclusion hereof.

In the drawings:

Fig. 1 is a side elevation of one of the intermediate boiler sections.

Fig. 2 is a section taken on line 2—2 of Fig. 1.

Fig. 3 is a section taken on line 3—3 of Fig. 1.

Fig. 4 is a section taken on line 4—4 of Fig. 1.

Fig. 5 is an elevation of the inner side of the front boiler section.

Fig. 6 is a section taken on line 6—6 of Fig. 5.

Fig. 7 is an elevation of the inner side of the rear boiler section.

Fig. 8 is a section taken on line 8—8 of Fig. 7.

Fig. 9 is a horizontal section taken on line 9—9 of Fig. 7.

Fig. 10 is a vertical longitudinal section of the boiler taken on line 10—10 of Figs. 1, 5 and 7.

The boiler comprises a front generally design-

inated 17, a rear section generally designated 18, and any desired number of intermediate sections generally designated 19, which fit against one another in face to face relation and are secured together by suitable tie-rods 20 which extend through all the sections, as well understood in the art. A single inclined grate comprises bars 21 supported in the assembled sections. The assembled sections form a fuel magazine *a* at one side of the upper portion of the boiler, a firebox *b* over the grate, an ash pit *c* below the grate, baffles *d* in the intermediate sections over the firebox at one side of the magazine *a*, a flue *e* for combustion gases above the baffle *d* and an upper flue *f* for conducting combustion gases to the stack, and water conduits *g*, *h* and *k* formed of communicatively connected chambers in the sections. The front boiler section 17 includes integral side and top walls, and an outer wall 27 and an inner wall 28 joined to the front wall by an inclined wall 29 which extends along the upper line of the inclined grate to form a water jacket in the front section which extends upwardly to the top wall of the section; walls 25 around the magazine door opening 22 and the firebox door opening 23; walls forming a section 30 of conduit *g*, a second 32 of conduit *h*, and a section 33 of water conduit *k*; and walls forming vertical water legs 34, 35 at the sides of the section 17, all of which sections and legs are communicatively connected for the flow of water therethrough. The walls of section 17 are also extended to form a vertically extending portion 37 and an inclined portion 36 which form a section of the inner side of the magazine *a* with a chamber therein communicatively connected to the water chamber in the front section. The side-legs 34', 35' of boiler section 17 below conduit-sections 30, 32 are of light web formation and are not provided with water chambers. The inner face of the front boiler-section 17 has an integral rib or bead 40 which extends along the sides and top of the front section 17 and ribs 37', 36' which are coplanar and adapted to fit against corresponding ribs of intermediate section 19. The front boiler-section is provided with a door 23' for closing firebox opening 23, a door 24' for closing the ash-pit opening 24, and a door 22' for closing the opening 22 for the fuel magazine. Openings 38 and 39 extend through the front section 17 for insertion of a tool for cleaning the flues *e*, *f*, and are normally closed by a removable plate 40'. The walls of section 17 at the outer side of and above the magazine door opening 22 are formed of webs and are not

hollow. A baffle 90 for steam from conduit *k* is formed at the inner side of the chamber which communicates with conduit *k* in the upper portion of section 17 and extends between the inner and outer walls of said chamber. A steam outlet 57^a is provided in the top wall of said chamber. An opening 91 in the lower portion of baffle 90 permits steam to pass from the lower portion of said chamber through the baffle to said outlet. Projections 59^a may be formed on the inner wall of the front section to conform to grate contour.

The rear boiler-section 18 includes integral side and top walls and an outer wall 45, an inner wall 46 connected by an inclined wall extending over the grate, to form a water chamber extending from the inclined wall to the top of said section; walls forming a section 49 of conduit *g*, a section 50 of conduit *h*, and a section 51 of conduit *k*; walls forming water legs 52, 53 extending upwardly from the chambers 49 and 50, respectively, to the upper portion of boiler-section 18; walls forming a vertical portion 54 and an inclined portion 55 of a section of the inner side of the fuel magazine *a*; walls forming a section of the flue *f*; walls 59 forming extensions overlying the end of the grate, all of which are provided with water chambers communicatively connected. The side legs 56 between the bottom walls of conduit sections 49 and 50 and the base of boiler-section 18 are formed of light webs and are not provided with water chambers. The inner side of rear section 18 is provided with a rib 57 along its sides and top and a rib or bead 58 on the inner sides of magazine section 54, 55, and a rib or bead 58' along the bottom of section of flue *f*, all of which are coplanar to fit against corresponding ribs on an intermediate section 19. An opening 59 for connection to a stack extends through the back section 18 from the flue *f*. An outlet 57 for steam is provided in the top wall of rear section 18 and an opening 57' is provided in the rear wall 47 for connection to a gauge safety valve. One or more openings 52^a may be formed in one side of the rear section for supplying secondary air to the firebox. Projections 59^a may be formed on the inner wall of the rear section to conform to grate contour.

Each intermediate section 19 comprises integral side and top walls, and walls forming sections 60, 61 and 62 of conduits *g*, *h* and *k*, respectively; walls forming a vertical water leg 63 extending upwardly from section 60; walls 64 formed of webs and not hollow at the outer side top of the magazine; hollow walls forming a vertical side portion 65 and an inclined portion 66 of the inner side of a section of the magazine *a*, the inclined side portion being communicatively connected by a narrow leg 66' with conduit-section 61; hollow walls forming a section of the flue *e*, a section of the flue *f*, and a baffle *d*, all of which have chambers therein communicatively connected for the flow of water therethrough. The sides of boiler-section 19 below the conduit-sections 60, 61 are formed of light webs as at 64', 63' and are not provided with water chambers. Each of the faces of the rear boiler-section 18 terminates in a faced rib 70 which extends around its sides and top. Each face of section 19 is provided with a rib 81 at the inner side of the magazine-section therein and reversely inclined ribs 82, 83 extending along the bottom of the flue *f*, all of which are adapted to fit against correspondingly faced ribs on other intermediate sections or a rear or front section of the boiler. The upper end of the ribs 81 terminate below the ribs 70 to

provide spaces for venting gas, steam or moisture around the fuel in the magazine *a* to the flue *f* for preventing combustion of the fuel in the magazine. The lower ends of reversely inclined ribs 82, 83 are spaced apart to permit soot from the flue *f* to drop into the firebox during the cleaning of said flue.

The lower ends of the grate-bars 24 are pivotally supported in lugs 90 which depend from the bottom wall of conduit-sections 60 and their upper ends are pivotally supported in recesses 91 formed in the inclined inner sides of the lower portion of the walls around conduit-section 61.

The sections of conduit *h* are disposed substantially at the upper end of the grate and at a considerably higher elevation than the conduit *g* and the webs forming side wall or leg portions between the conduit *h* and the base of the boiler are of greater height than when the conduit *g* is disposed at the lower end of the grate. This results in greatly reducing the weight of the boiler sections, increases the combustion space in the firebox, also shortens and provides a greater angle in the inclined portion of the side-portions 64 between the upper end of the grate and the adjacent vertical outer side of the throat through which the coal is fed to the grate. This keeps the outer side of the magazine dry and above evaporating temperature to eliminate any tendency of the wall to rust due to moisture.

The contiguous walls forming sections of conduits *g*, *h* and *k* in the front, rear and intermediate boiler sections have openings for nipples 93 for communicatively connecting said sections, as well understood in the art. The front wall of the front section at conduit sections 30, 32 and 33 is provided with tapped openings for closure plugs.

The baffles *d* in the assembled boiler sections 40 direct the hot gases from the firebed longitudinally forwardly and into the flue *e* from which the gases pass longitudinally forwardly into the front boiler section and thence upwardly and longitudinally rearwardly through the flue *f* to the stack for an efficient interchange of heat between the flue gases and the boiler sections. The ribs 53 on rear boiler-section 18 and ribs 82 on the intermediate sections prevent any great amount of flow of gases from flue *e* to flue *f*.

The walls in the boiler sections 19 around flue *f* are shaped to form an inwardly and upwardly inclined bottom, a vertical outer side and a horizontal top with legs for the circulation of water. The walls in the intermediate sections forming the flue *e* and baffles *d* extend upwardly and inwardly from the water legs 63 in parallel relation with the bottom of flue *f*. This inclination and the reverse inclination of ribs 82 and 83 facilitate the cleaning of the flues.

In operation, the fuel stored in the magazine *a* of the assembled front, intermediate and rear boiler sections is automatically fed into the firebox at the upper portion of the grate through the openings between the legs 66'. Some of the combustion gases pass upwardly in the firebox to the baffles *d* in the intermediate sections and the spaces between said baffles into the flue *e* where they flow forwardly to the front boiler section 17 in which they pass upwardly to the front of the flue *f* and then flow rearwardly to the opening 59 in the rear section 18 of the stack. The heat is efficiently transferred through the walls of the sections around the firebox, the baffles, the flues *e* and *f*, and the water legs.

The invention exemplifies a boiler of sectional

magazine feed type with a single inclined grate which includes water conduits at the sides of the boiler, respectively, one of said conduits being disposed substantially higher than the other and at the lower and upper ends of the inclined grates and below the conduits of web formation, which result in an increase of combustion space in the firebox, and a substantial reduction in the weight of the sections which are usually formed of cast metal. The invention also exemplifies a boiler of this type which provides for an efficient interchange of heat to the water in the boiler sections from the combustion products in the firebox, through upwardly and inwardly inclined baffles to a lower duct or flue which directs the gases longitudinally forward and then rearwardly through the upper flue to the stack. The invention also exemplifies a boiler of this type in which gases in the magazine are drawn into the flue which leads to the stack for preventing combustion in the magazine. The invention also provides reversely inclined ribs on the sections for directing the soot from the upper flue to the firebox during cleaning operations.

The invention is not to be understood as limited to the details described, since these may be modified within the scope of the appended claims without departing from the spirit and scope of the invention.

Having thus described the invention, what I claim as new and desire to secure by Letters Patent is:

1. In a boiler of sectional magazine feed type with a firebox having an inclined grate extending transversely across the box, a boiler-section comprising walls forming sections of water conduits at the sides, respectively, one of said conduit sections being disposed substantially higher than the other and at one side of the upper end of the grate; side-legs of web-formation between the conduit sections and the base of the boiler section; a water leg extending upwardly from the lower conduit section; a fuel magazine section having an outer side of web-formation, an inclined lower portion at its inner side with a throat for fuel between said inclined portion, and a water leg extending directly between said inclined portion and the higher water conduit section; and a longitudinal flue section at the opposite side of the magazine having an upwardly and inwardly inclined bottom, the inner side of the fuel magazine and the flue sections having water chambers therein.

2. In a boiler of sectional magazine feed type with a firebox having an inclined grate extending transversely across the box, a boiler-section comprising walls forming sections of water conduits at the sides, respectively, one of said conduit sections being disposed substantially higher than the other and at one side of the upper end of the grate; side-legs of web-formation between the conduit sections and the base of the boiler section; a water leg extending upwardly from the lower conduit section; a fuel magazine section having an inclined lower portion at its inner side with a throat for fuel between said inclined portion, and a water leg extending directly between said inclined portion and the higher water conduit section; a longitudinal flue section at the opposite side of the magazine having an upwardly and inwardly inclined bottom, the inner side of the fuel magazine and flue sections having water chambers therein; and a baffle extending upwardly and inwardly under and below the flue section.

3. In a boiler of sectional magazine feed type with a firebox having an inclined grate extending transversely across the box, a boiler-section comprising walls forming sections of water conduits at the sides of the sections, respectively, substantially at the upper and lower ends of the inclined grate, respectively; the upper end of the grate being disposed directly at the inner side of the upper conduit a water leg extending from the lower conduit section upwardly to the upper portion of the section; legs of web-formation between said conduit sections and the base; a fuel magazine section having an inclined bottom at its inner side and a throat between the lower end of the inclined bottom and the higher conduit section; a water leg connecting with the higher conduit section and the lower end of the inclined bottom; and a longitudinal flue-section having a water chamber therein, at opposite side of the magazine.

4. In a boiler of sectional magazine feed type with a firebox having an inclined grate extending transversely across the box, a boiler-section comprising walls forming sections of water conduits at the sides of the sections, respectively, said conduit sections being disposed substantially at the upper and lower ends of the grate, respectively, the upper end of the grate being disposed directly at the inner side of the upper conduit the conduit section at the upper end of the grate having an inclined inner side portion provided with means for supporting the upper end of the grate; a water leg extending from the lower conduit section upwardly to the upper portion of the section; legs of web-formation between said conduit sections and the base; a fuel magazine section having an inclined bottom at the inner side and a throat for fuel between the inclined bottom and the water leg connecting with the conduit section at the upper end of the grate; and a water leg extending directly between the higher conduit section and the lower end of the magazine.

5. In a boiler of sectional magazine feed type with an inclined grate, a boiler-section comprising walls forming sections of water conduits at the sides of the sections, respectively; a water leg extending upwardly from one of said conduit sections to the upper portion of the boiler-section; a fuel magazine section at one side of the boiler-section; a longitudinal flue section at the opposite side having an upwardly and inwardly inclined bottom, a substantially vertical outer side and a substantially horizontal top, the flue-section having a surrounding water chamber; and reversely inclined ribs on the faces of the boiler-section having an opening between their lower ends for the passage of soot from the flue to the firebox.

6. In a boiler of sectional magazine feed type with an inclined grate, a boiler-section comprising: walls forming sections of water conduits at the sides of the sections and at the upper and lower ends of the grate, respectively; a water leg extending upwardly from one of said conduit sections to the upper portion of the boiler-section; a fuel magazine section at one side of the boiler-section; a longitudinal upper flue-section at the opposite side having an upwardly and inwardly inclined bottom, a substantially vertical outer side, and a substantially horizontal top, the flue-section and inner side section of the magazine having water chambers; reversely inclined ribs on the faces of the boiler-section having an opening between their lower ends for

the passage of soot from the flue to the firebox; and a flue-section under the bottom of the upper flue having spaces on its faces under the openings between the ribs.

7. In a boiler of sectional magazine feed type with an inclined grate, a boiler-section comprising: walls forming sections of water conduits at the sides of the section, respectively; a water leg extending upwardly from one of said conduit sections to the upper portion of the boiler-section; a fuel magazine section at one side of the boiler-section; a longitudinal flue section at the other side, the magazine section having a vertical upper portion and an inclined lower portion and vertical ribs on its faces for fitting contiguous boiler-sections and cut-away spaces at the upper ends of the ribs for drawing gases from the magazine into the flue, the flue-section and inner-side of the magazine section having water chambers therein, said cut-away spaces having their lower ends terminating a substantial distance above the flue.

8. In a boiler of sectional magazine feed type with an inclined grate, a boiler-section comprising: walls forming sections of water conduits at the sides of the sections, respectively; a water leg extending upwardly from one of said conduit sections to upper portions of the boiler-section; a fuel magazine section at one side of the boiler-section; a longitudinal flue at the other side, the magazine section having a vertical upper portion and an inclined lower portion and ribs on its faces on the vertical and inclined portions for fitting contiguous boiler-sections and cut-away spaces at the upper ends of the ribs for drawing gases from the magazine into the flue, the flue-section and inner-side of the magazine section having water chambers therein, said cut-away spaces having their lower ends terminating a substantial distance above the flue.

9. In a boiler of sectional magazine feed type with an inclined grate, a boiler-section comprising: walls forming sections of water conduits at the sides and at the top of the section, respectively; a water leg extending upwardly from one

of said conduit sections to upper portions of the boiler-section; a fuel magazine section at one side of the boiler-section; a longitudinal flue at the other side under the top-conduit section, 5 the magazine section having a vertical upper portion and an inclined lower portion and vertical ribs on its faces for fitting contiguous boiler-sections and cut-away spaces at the upper ends of the ribs for drawing gases from the magazine into the flue, the flue-section and inner-side of the magazine section having water chambers therein, said cut-away spaces having their lower ends terminating a substantial distance above the lower portion of the top-conduit section.

10. In a boiler of sectional magazine feed type with an inclined grate, a boiler-section comprising: walls forming sections for a water conduit at the sides of the sections, respectively; a water leg extending upwardly from one of said conduit sections to the upper portion of the boiler-section; a section of a fuel magazine at one side of the boiler-section; a longitudinal upper flue-section having an upwardly and inwardly inclined bottom, a vertical outer side and a substantially horizontal top, said bottom extending contiguously upwardly and inwardly from one side of the boiler-section and under the upper flue; and an inwardly and upwardly inclined baffle having a water chamber therein under and forming the bottom of the lower flue-section; and reversely inclined ribs at the bottom of the upper flue.
